UNITED STATES PATENT OFFICE.

EMORY McCLUNG, OF CLARKSBURG, WEST VIRGINIA, ASSIGNOR OF ONE-HALF TO C. M. ERNST, OF CLARKSBURG, WEST VIRGINIA.

DESIGN FOR A CHIMNEY-TOP.

No. 39,621.

Specification for Design.

Patented Oct. 13, 1908.

Application filed April 22, 1908. Serial No. 428,853. Term of patent 7 years.

To all whom it may concern:

Be it known that I, EMORY McCLUNG, a citizen of the United States, residing at Clarksburg, in the county of Harrison and State of West Virginia, have invented a new, ornamental, and original Design for a Chimney-Top, of which the following is a specification, reference being had therein to the accompanying drawing, forming part thereof.

My design is the representation of a chimney top, having in its body, at the sides and corners, longitudinally - extending grooves, and near the top is a plurality of horizontal beads, the beads representing a step - like structure at each side.

I claim:

The ornamental design for a chimney-top, as shown and described.

EMORY McCLUNG.
